UNITED STATES PATENT OFFICE.

JOHN F. GEIBEL, OF BUFFALO, NEW YORK, ASSIGNOR TO MASTER METAL PRODUCTS, INC., OF BUFFALO, NEW YORK, A CORPORATION OF NEW YORK.

SANITARY WASTE CAN.

Application filed October 7, 1925. Serial No. 60,949.

This invention relates generally to sanitary waste cans or garbage receptacles, but more particularly to certain novel improvements in the cover or closure operating mechanism of such cans.

One of its objects is to provide a cover-lifting mechanism which is simple, compact, strong and durable in construction, and which is composed of few parts, permitting 10 its manufacture at a reasonable cost.

Another object of the invention is to provide a foot-operated cover lifting mechanism having reliable means for cushioning or 15 yieldingly resisting the opening of the cover beyond a predetermined point and also for 15 insuring its prompt return to closed position.

In the accompanying drawings:

Figure 1 is a side elevation, partly in section, of a garbage receptacle constructed in 20 accordance with my invention. Figure 2 is a rear view thereof, partly in section. Figure 3 is a horizontal section of the same on line 3—3, Fig. 1. Figure 4 is an enlarged fragmentary transverse section on line 4—4, 25 Fig. 2. Figure 5 is a perspective view of the yieldable cover stop or spring.

Similar characters of reference indicate 30 corresponding parts throughout the several views.

In the preferred embodiment of the invention shown in the drawings, the same comprises an outer can-body or container 10 of cylindrical form, open at its ends, and constructed of sheet metal or other suitable 35 material. Removably contained within the can-body is a receptacle 11 in the form of a pail for receiving the garbage or other waste materials, the same having a bail 12 pivoted to fold into it.

The upper end of the can-body 10 is provided with a vertically swinging cover 13 to the rear side of which a strap 14 is secured, said strap having a pair of depending 40 hinge lugs or ears 15 which engage a horizontal hinge-pin 16 supported on a pair of similar hinge lugs 17 projecting rearwardly 45 from a bracket 18 attached to the rear side of the can-body, as shown in Figs. 1, 2 and 4.

Located at the lower end of the can-body 50 is a combined support and actuating device for the receptacle 11 and cover 13, respectively, said device serving to properly support or sustain the receptacle within said can-body above the floor, as shown in Fig.

1, and to raise the cover to its open position, shown by dotted lines in the same figure. To this end, this device is preferably in the form of a horizontally-disposed oscillating member or rock shaft 19 located eccentric to or at one side of the center of 55 the can-body and supported near its ends in bearing-openings 20, 20 formed in the latter. That portion of the shaft contained within the can-body subtends a sufficient portion of the curved wall thereof to reliably support 60 the receptacle in the position shown in Figs. 1 and 2. At its rear end, this rock shaft has an offset curved portion or crank arm 21 extending transversely of and part way around the can body in proximity thereto 65 and terminating in a rearwardly-facing end portion 21^a disposed substantially radially of 70 said can-body and below the hinge-pin 16. This crank arm is connected by an upright link 22 with an extension 23 projecting from 75 the rear end of the cover hinge strap 14, the upper end of said link having a loop 24 engaging an opening 25 in said extension, as shown in Fig. 4. The front end of the rock shaft 19 terminates in a forwardly-facing 80 crank-arm 26 having a pedal 27 attached thereto. When the latter is depressed, the shaft is oscillated in a direction to cause 85 its crank 21 to pull downward on the link 22 and open the cover, as indicated by dotted lines in Figs. 1 and 4.

It will be noted that the rock shaft 19 extends substantially from the front to the rear end of the can-body with the crank arms 21, 26 located approximately at right 90 angles to each other and at an obtuse angle to the shaft. This arrangement not only permits the ready mounting of the shaft on the can-body but it brings the pedal at the front portion of the can-body where it extends forwardly toward the user and is in 95 a position to be conveniently operated.

For the purpose of cushioning or yieldingly resisting the opening movement of the cover beyond a substantially forwardly inclined position and also for insuring its prompt return to closed position when the pedal 27 is released, a yieldable stop is provided. As shown in Figs. 4 and 5, this stop 100 is preferably in the form of a flat spring 28, approximately Z-shaped in cross-section, which passes intermediate its ends around the upper side of the hinge-pin 16 and oc-

cupies the space between the depending lugs 15 of the hinge-strap 14. The upper portion 29 of said spring passes through the opening 25 in the strap-extension 23 and is bent 5 upwardly over the adjacent upper side thereof, while its lower portion or tail 30 normally extends downwardly and rearwardly a suitable distance beyond the lugs 15.

10 When the cover 13 is opened, this tail encounters the lower end of the transverse bar or web 31 of the hinge-bracket 18 and yieldingly resists the opening of the cover to a point beyond its fulcrum, thus not only

15 preventing danger of the cover remaining open due to neglect of the user but always insuring its quick return to closed position. Furthermore, the spring 28 is so mounted that no separate fastenings are required to 20 hold it in place and also that it offers no resistance until the cover practically reaches its fully opened position, thereby permitting the easy and ready opening of the cover with very little effort.

25 This improved cover-operating mechanism for sanitary waste cans and the like is manifestly simple, compact and inexpensive in construction, it is neat and sightly in appearance, and its actuating parts are located 30 close to the can-body and wholly at one side thereof, whereby the can can be placed against the wall or in a corner convenient for use without interfering with the opening and closing movements of the cover.

35 I claim as my invention:—

1. A device of the character described, comprising a can-body, a cover hinged to the rear top portion thereof, a rock shaft journaled in the wall of the can body at one side 40 of its center, said shaft being provided at its front end with a forwardly facing crank, and at its rear end with a lateral portion extending part way around the exterior of the can-body and terminating at its end in a substantially radial crank-arm, the front 45 crank constituting a pedal for actuating the shaft, and means for connecting crank-arm with the hinged portion of the cover.

2. A device of the character described, 50 comprising a can-body, a cover hinged to the rear top portion thereof, a rock shaft extending substantially from the front to the rear of the can-body at one side of its center and journaled in the side wall thereof, said shaft being provided at its front end with a pedal-crank and at its rear end with a lateral portion extending part way around the exterior of the can-body and terminating substantially centrally of the 55 rear side of the latter in a radial crank-arm located below the hinge point of the cover, and means for connecting said crank-arm with the hinged portion of the cover.

60 3. A device of the character described, 65 comprising a can-body adapted to receive a

waste receptacle, a cover hinged to the top thereof, a rock shaft journaled in the lower end of the can-body at one side of its center, said shaft being provided at its front end with a forwardly-facing pedal-crank and at 70 its rear end with a lateral portion extending part way around the exterior of the can-body and terminating at its end in a rearwardly-facing radial crank-arm, the intermediate portion of the shaft contained within 75 in the can-body forming a support for the receptacle, and means for connecting the radial crank-arm with the hinged portion of the cover.

4. A device of the character described, 80 comprising a can-body, a cover hinged to the top thereof, means mounted on the can-body for swinging the cover to its open position, and a combined stop and return spring for limiting the opening of the cover 85 beyond a predetermined point and for causing the return of said cover to its closed position when the cover-actuating means are released, said combined stop and return spring including a member applied to the 90 hinged portion of the cover to move therewith and having a yieldable tail piece arranged to engage the adjoining part of the can-body only in the open position of the cover. 95

5. A device of the character described, comprising a can-body, a cover hinged to the top thereof, means mounted on the can-body for swinging the cover to its open position, and a yieldable stop applied to the 100 hinge portion of the cover and adapted to abut against the adjoining part of the can-body in the fully-opened position of the cover, said stop being normally clear of the can-body and movable in an unobstructed 105 path with the cover during the major part of its opening movement.

6. A device of the character described, comprising a can-body, a cover therefor, hinge members including a pivot pin applied 110 to the can-body and its cover, foot-operated means for raising the cover, and a flat spring carried by the cover hinge member and extending downwardly around said pivot, the free lower end of said spring being normally clear of the adjacent part of the can-body and adapted to engage such part only in the open position of the cover to yieldingly resist its opening beyond a predetermined point. 115

7. A device of the character described, comprising a can-body, a cover therefor, hinge members, including a pin, applied to the can-body and its cover, foot-operated means for raising the cover, and a substantially 120 Z-shaped flat spring extending over the hinge-pin and having its upper portion in engagement with the cover hinge member, the lower portion of said spring being normally free and yieldable and arranged to 125 130

engage a part of the can-body at a predetermined point in the opening movement of said cover.

8. A device of the character described, comprising a can-body adapted to receive a waste receptacle, a cover hinged to the can-body, a rock shaft journaled in and extending through the lower end of the can-body,

said shaft being provided at its front end with a foot pedal and at its rear end with a ¹⁰ crank arm, the intermediate portion of the shaft contained within the can-body forming a support for the receptacle, and means for connecting said crank arm with the hinged portion of the cover.

JOHN F. GEIBEL.
